UNITED STATES PATENT OFFICE.

AMOS NICKERSON, OF SOMERVILLE, MASSACHUSETTS.

HAMMOCK-SPREADER.

SPECIFICATION forming part of Letters Patent No. 320,276, dated June 16, 1885.
Application filed March 30, 1885. (No model.)

To all whom it may concern:

Be it known that I, AMOS NICKERSON, of Somerville, in the county of Middlesex and State of Massachusetts, have invented a new and useful Improvement in Hammock-Spreaders, of which the following, taken in connection with the accompanying drawings, is a specification.

My invention relates to devices for keeping the ends of the hammock distended, so that the same shall be comfortable to the user, the object being to make the spreader in such a manner that it shall be absolutely safe—that is, to hold each cord in place and not to be accidentally thrown out of place. These objects I obtain by the mechanism shown in the accompanying drawings, in which—

Figure 1 is a perspective view of a hammock with my improved spreader attached. Fig. 2 is an enlarged view in perspective, showing more clearly my device and how it is applied. Fig. 3 is a perspective view of my spreader. Fig. 4 is a detail showing the character of the notches.

In the drawings, A represents the body of the hammock, having the usual suspending-ropes, B B. The spreader-bar C is illustrated at Fig. 3, and consists of a bar of wood or other suitable material having T-shaped notches c c. The exact method of making this notch is shown in Fig. 4, in which c is a kerf, made at right angles to the line of the rod C C, and c' c' is a longitudinal groove extending both ways from said kerf.

The use of my spreader consists in so placing it from the under side of the hammock that two of the cords of each alternate interior knot, b, shall pass through one of the notches and separate to exterior knots, b', Figs. 1 and 2, or all of the cords of the net may pass through the notches, two in each, the idea being to so place the cords in relation to the notch that the strain shall always be in the direction of the length of the spreader—that is, against the ends c' c', Figs. 3 and 4, of the notches—so that there is no tendency for the cords to slip out.

By this construction of the spreader-rod I obtain a secure holder for the hammock and at the same time one which can be easily detached from the hammock when desired.

I claim as my invention and desire to secure by Letters Patent—

A hammock-spreader, C, having notches c c, each enlarged at its base in both directions parallel to the length of the spreader, substantially as described, and for the purpose set forth.

In testimony whereof I have signed my name to this specification, in the presence of two subscribing witnesses, on this 27th day of March, A. D. 1885.

AMOS NICKERSON.
